UNITED STATES PATENT OFFICE

2,453,976

BALL GATE AND ELEVATING MECHANISM

Lyndon A. Durant and Gordon Horlick, Chicago,
Ill., assignors, by direct and mesne assignments,
to Royal Patent Corporation

Application October 23, 1945, Serial No. 624,002

2 Claims. (Cl. 273—122)

1

Our invention relates to ball gate and elevating mechanism of the character wherein the balls are projected upon an inclined board for gravitation thereover into contact with targets such for example bumper switches or the like. The invention has for its principal object the provision of an improved structure of this character which will be efficient in operation and economical in manufacture.

Another object of the invention is the provision in a game apparatus of the character herein-after more fully described where the ball outlet gate is utilized for the two-fold purpose that of retaining the spent balls at the outlet or return opening until released by the gate and also that of functioning to rebound the balls back upon the board for further play until the balls are spent. In this character of the gate the balls have greater animation and prolonged play.

Yet a further and equally important object of the invention is the novel and effective means for elevating the returned balls to position for projection upon the play board for gravitation thereupon. In this character of the invention it is the aim to bring the ball from a return runway to a position before the projector by mechanism which acts upon the ball to roll the same from the return runway to said projecting position, as distinguished from the mechanism which slaps or bats the ball to that position, the latter arrangement invariably resulting in the ball bouncing back or rebounding into the return runway, consequently requiring several operations to bring the ball to projecting position.

Another and equally important object of the invention is the provision of a simple arrangement for latching the ball retaining gate in ball releasing position and for effecting movement of the gate into ball retaining position.

A still further object of the invention is the provision of means, operable by the ball elevator mechanism, for releasing the ball gate for movement into ball retaining position.

Other objects will appear hereinafter.

The invention consists in the novel combination and arrangement of parts to be herein-after described and claimed.

The invention will be best understood by reference to the accompanying drawings showing the preferred form of construction, and in which:

Fig. 1 is a fragmentary perspective view of the under side of an inclined play board illustrating certain of the mechanism embodied in our invention associated therewith;

Fig. 2 is a fragmentary perspective top plan view of the front end of the play board, a glass top being removed;

Fig. 3 is a perspective view of the ball elevating mechanism embodied in the invention;

Fig. 4 is a sectional detail view taken substantially on line 4—4 of Fig. 2;

2

Fig. 5 is a sectional detail view taken substantially on line 5—5 of Fig. 1;

Fig. 6 is a sectional detail view taken substantially on line 6—6 of Fig. 1.

5 The several drawings illustrate the preferred form of construction by which the several objects of our invention are accomplished.

In this connection 10 indicates a cabinet which may be of any well known construction. This 10 cabinet includes a bottom wall 11, side and end walls 12 and 13 respectively, and a glass top 14 through which may be viewed the play board 15 arranged within the cabinet at an inclination with respect to the horizontal and beneath the glass top 14.

15 The play board 15 at one side includes a ball ramp 16 through which balls 17 are projected by a projecting device 18, herein-after more fully described. The upper end portion of this ramp (not shown in the drawings) opens upon the upper end portion of the board 15 to discharge the balls thereon for gravitation down the board.

20 At the lower end portion 19 of the board 15 is an elongated outlet opening 20, the balls 17 being guided thereto by the converging edges 21 of a filler block 22. These edges 22 are provided with rebound strips 22' preferably formed of rubber or the like for rebounding the balls back into play upon the board 15.

25 30 Balls are retained from passage through the outlet opening 20 by a gate 23. This gate comprises a substantially U-shaped bar 24 the end portions 25 of which are pivotally connected as at 26 to the parallel arms 28 of a mounting bracket

35 35 27 secured as at 29 to the under side of the block 22. The end portions 25 of the bar 24 have spaced depending arms 29 and 30. The arm 29 has secured thereto one end portion of a spring 31, the opposite end portion of the spring 31 being connected to an end portion of a plate 32 secured to the underside of the play board 15 as at 33. The inner end 34 of the plate 32 is adapted to engage the arm 29 to limit pivotal movement of the gate to the position shown in Figs. 5 and 6.

40 45 On the face of the bar 24 is a rebound strip 24' similar to, and for the same purpose as the strips 22'.

45 50 Means are provided for releasably latching the gate in ball releasing position (shown in dotted lines in Fig. 6). This means in its preferred form of construction comprises a bracket 35 having an upturned end portion 36 secured as at 37 to the block 22. The opposite end portion of the bracket includes an inverted substantially U-shaped portion 38 secured as at 39 to the under side of the board 15. To the bracket 35 adjacent the upturned end 36 is a lug 40 and pivotally secured to this lug 40 as at 41 is a limb 42 of a substantially U-shaped latch bar 43, the opposite limb 44, of this bar being pivotally secured as at

45 to the end portion 46 of the bracket 35. In the bight portion 47 of the latch bar 43 is a keeper notch 48 adapted to engage a latch shaped end portion 49 provided by the arm 30, when the gate is pivoted to the position shown in dotted lines in Fig. 6, by means presently explained. The latch portion 49 of the arm 30 will engage in the keeper notch 48 and the gate will be thereby held in the ball releasing position as shown in dotted lines in Fig. 6. In this position of the gate the balls 17 are free to pass through the ball outlet opening 20.

The means for pivoting the gate to ball releasing position includes a release bar 50 having a depending end portion 51 secured as at 52 to a supporting bar 53 slidably supported by spaced brackets 54 and 55 secured as at 56 to the underside of the board 15. This release bar 50 has an upwardly extending end portion 57 to which is connected a stop finger 58 hereinafter more fully described.

On the support bar 53 is an angled plate 59 to which is connected a finger 60. This finger 60 is adapted to be engaged by the end portion of the slide bar of a standard coin slide (not shown). To the bracket 54 is secured one end of a spring 62, the other end of this spring being connected to the supporting bar 53 as at 63. The arrangement is such that when the release bar 50 is moved rearwardly relative to the board 15, against the action of the spring 62 this bar 50 will engage the arms 29 and 30 and pivot the gate against the action of the spring 31 into ball release position, in which position the latch end 49 will engage the keeper notch 48. The gate will be held in this position until the latch end 49 is disengaged from the keeper notch 48 in a manner explained.

As the balls 17 pass through the outlet opening 20 they drop upon an inclined track 64 comprising spaced flat rails 65 having their end portions 66' secured as at 67 to the under side of the board 15. In rolling down the track the balls will engage between the rails 65 and be guided thereby to a position for elevation by a ball elevator 66. Adjacent the outlet opening 20 there is provided a shield 68 to prevent dislodgement of the balls 17 as they drop from the board 15 through the outlet opening 20 onto the track 64.

When the ball gate 23 is in ball release position the stop finger 58 will be moved transversely of the track 64 and block the balls in their movement down the track 64.

This ball elevator 66 comprises a mounting block 68 secured to a side wall 12 of the cabinet. The block 68 carries a plate 69 having an angled end portion 70 to which is pivotally connected as at 71 a lifting dog 72. This lifting dog 72 has a beak portion 73 adapted to move between the rail 65 into engagement with a ball and as the dog is pivoted the ball engaged by the dog will roll, as distinguished from being struck by the dog, along the edge 74 of the dog onto a platform 75 of a projector 76 before a plunger 77 thereof for projection along the ramp 16 toward the upper end of the board 15.

The pivotal movement of the lifting dog 70 is effected by an operating lever 78, one end portion of which provides a roller 79 engaging the dog 12 as shown in Fig. 3. This lever 78 is pivoted to the block 68 as at 80 and has its outer end portion 81 projecting through a slotted plate 82 secured to the outer face of the front wall 13. This end portion of the lever is shaped to provide a finger grip 83. Secured to the block 68 as at 84 is one 75

end portion of a spring 85, the opposite end portion of this spring being connected at 86 to the lifting dog 72, the spring serving to return the dog 72 and the lifting lever to their original positions as shown in Fig. 3.

The projector 76 may be of any approved construction which includes the spring controlled plunger 77 having the exterior finger button 81.

As shown in Fig. 3 when the lifting lever 83 is pivoted to pivot the lifting dog 72 against the action of the spring 85, the end portion 88 thereof will engage the end portion 88' of the limb 44 of the latch bar 43 in a direction to disengage the keeper notch 48 from the latch portion 49 of the gate 23 to permit the gate 23 to pivot to ball retaining position as shown in full lines, in Figs. 5 and 6.

By the employment of the preferred construction herein described we provide a game apparatus capable of accomplishing the several objects of the invention in an efficient manner at the minimum of cost in manufacture.

25 While we have illustrated and described the preferred form of construction for carrying our invention into effect, this is capable of variation and modification without departing from the spirit of the invention. We, therefore, do not wish to be limited to the precise details of construction set forth, but desire to avail ourselves 30 of such variations and modifications as come within the scope of the appended claims.

Having thus described our invention, what we claim as new and desire to protect by Letters Patent is:

35 1. The combination with a pivotally movable ball gate of an amusement apparatus and a latch member therefor, of a supporting structure, a ball elevating member pivotally carried by the structure, an operating handle pivotally carried by the
40 supporting structure and having an end portion engaging the ball elevating member and the latch member for simultaneously operating the ball elevating member and the latch member to release the latch member from engagement with
45 the ball gate when the ball elevating members is elevated by said operating handle.

50 2. The combination with a pivotally movable ball gate of an amusement apparatus and a latch member therefor, of a supporting structure, a ball elevating member pivotally carried by the structure, an operating handle pivotally carried by the supporting structure and having an end portion engaging the ball elevating member and the latch member for simultaneously operating the ball elevating member and the latch member to release the latch member from engagement with the ball gate when the ball elevating member is elevated by said operating handle, there being roller engagement between said end portion of the operating handle and said ball elevating member.
